CLAIM

[**] Term: 14 Years

The ornamental design for a reel bobbin for a wire saw for semiconductors, as shown and described.

[21] Appl. No.: 74,079

DESCRIPTION

[22] Filed: Aug. 5, 1997

FIG. 1 is a perspective view of a reel bobbin for a wire saw for semiconductors;

[51] LOC (6) Cl. 15-09

FIG. 2 is a front elevational view thereof, the rear elevational view, the top plan view, and the bottom plan view being identical with FIG. 2;

[52] U.S. Cl. D15/138; D15/78

FIG. 3 is a right side elevational view thereof, the left side elevational view being a mirror image of FIG. 3; and, FIG. 4 is a referential view showing location of the present article in a wire saw for semiconductors.
